UNITED STATES PATENT OFFICE.

CHARLES F. MARKLAND, OF PITTSBURG, PENNSYLVANIA.

CUSPIDOR.

SPECIFICATION forming part of Letters Patent No. 257,137, dated April 25, 1882.

Application filed November 9, 1881. (No model.)

To all whom it may concern:

Be it known that I, CHARLES F. MARKLAND, of Pittsburg, in the county of Allegheny and State of Pennsylvania, have invented certain new and useful Improvements in Cuspidors, of which the following is a specification.

My invention is a cuspidor constructed as fully described hereinafter, so as to prevent accidents from upsetting or moving.

In the drawings, Figure 1 is a perspective view of my improved cuspidor. Fig. 2 is a vertical section, reduced size. Fig. 3 is a section, showing a modification.

Cuspidors as ordinarily constructed and placed in passage-ways and exposed places are apt to be overturned from contact with the feet of parties passing the same, for which reason it is common to use a detachable mat of oil-cloth or other material beneath each article. This, while preventing the contents to a certain degree from being spilled on the carpets or floors, does not prevent the overturning of the article, which it is the object of my invention to accomplish, and which object I secure by connecting the cuspidor permanently with the mat.

The mat B may be of oil-cloth, riveted to the cuspidor A, as shown in Fig. 3, affording a wide base, that will prevent the article from tipping over, or it may be of metal soldered

to the body of the cuspidor, or it may be of papier-maché, molded to form a rim and flange, *f*, that impart stiffness, as in Figs. 1 and 2, and connected or otherwise secured to the body *A*. In any case the desired result is effectually secured.

Cuspidors used on shipboard are not only liable to be overset, as described, but also to slide out of place and become reversed by the movement of the vessel. I prevent this by providing the base of the cuspidor with a central screw, *s*, Fig. 3, or with two or more pins, as shown in Fig. 2, which serve to prevent sliding, and maintain the article flat on the floor or deck.

I claim—

1. A cuspidor provided with a flat rigid base-plate or platform secured to its bottom and extended laterally beyond its body, substantially as and for the purpose set forth.

2. The combination, in a cuspidor, of the body *A*, mat *B*, and one or more securing-pins *s*, as specified.

In testimony whereof I have signed my name to this specification in the presence of two subscribing witnesses.

CHARLES F. MARKLAND.
